STRIP ALIGNING MEANS

Irving S. Bodkin, New York, N. Y., assignor to
 Conrad Razor Blade Co. Inc., Long Island City,
 N. Y., a corporation of New York

Application February 10, 1932, Serial No. 592,173
 Renewed September 22, 1938

29 Claims. (Cl. 51—80)

The invention relates to an improved means for aligning and supporting strips of metal while traveling lengthwise to maintain their edges in proper position or alignment for grinding and/or honing the edges, or both, and/or stropping said edges, and for keeping such edges from contact with undesired objects or parts of the machine that would injure the sharpened edges.

The invention includes inserting individual aligning means successively within the perforations or apertures of a metal strip which may be used for the making of razor blades, retaining the aligning means within the apertures and guiding the same against vertical and transverse movements while the strip is being propelled for grinding or honing or stropping, successively removing the aligning means from the strip when grinding or honing or stropping is done, and returning the aligning means to the starting point to be re-inserted into the apertures of the strip.

The invention comprises novel details of improvements that will be more fully hereinafter set forth, and then pointed out in the claims.

Reference is to be had to the accompanying drawings, forming a part thereof wherein:

Fig. 1 is a plan view of a grinding or honing machine, embodying the invention.

Fig. 2 is a vertical longitudinal view of the machine.

Fig. 3 is an enlarged section on line 3—3, Fig. 2, illustrating devices to feed aligning means to the strip.

Fig. 4 is an enlarged section on line 4—4, Fig. 1.

Fig. 5 is an enlarged section on line 5—5, Fig. 1, showing interlocked sharpening, such as grinding, or honing, or stropping, wheels.

Fig. 6 is a perspective sectional view of a guide, or track used in guiding the steel strip and retaining the aligning means within the apertures of the strip and against vertical and transverse movements.

Fig. 7 is a section on line 7—7 Fig. 6, showing aligning means retained in the apertures in the strip, while the strip is being propelled in the direction indicated by the arrow.

Fig. 8 is an enlarged edge view of the feeding mechanism for the strip aligning means.

Fig. 9 is a section on line 9—9, Fig. 8.

Fig. 10 is a side view of Fig. 8, showing the feeding mechanism for the aligning means.

Fig. 11 is a section on line 11—11, Fig. 8.

Fig. 12 is a sectional and diagrammatic view of the feeding mechanism for the aligning means showing the feeder pawl disengaged from a ball in one of its positions.

Fig. 13 is a side elevation of the guiding device for the aligning means.

Fig. 14 is a rear elevation of the feeding device for the aligning means looking from the right hand side of Fig. 13.

Fig. 15 is a section on line 15—15 in Fig. 14.

Fig. 16 is a section on line 16—16 in Fig. 14.

Fig. 17 is a side of the steel-strip propelling-means and discharging mechanism of the aligning means.

Fig. 18 is a plan view of Fig. 17 partly in section on line 18—18, Fig. 17.

Fig. 19 is a section on line 19—19 in Fig. 17.

Fig. 20 is a detail view showing a section of the retainer for the aligning means to resist downward thrust of the sharpening wheel.

Fig. 21 is a similar view of retainer for the aligning means to resist upward thrust of the sharpening wheel.

Figs. 22 and 23 are sectional views showing the aligning means supporting the steel strip against downward and upward thrusts, respectively, of the interlocked sharpening wheels.

Fig. 24 is an enlarged longitudinal section showing the aligning means in the apertures of the steel strip and in the retainer for supporting the strip for grinding, honing or stropping while the strip is propelled in the direction of the arrow.

Fig. 25 is an enlarged section of another device to feed aligning means to the strip.

Fig. 26 is an enlarged edge section on line 26—26 in Fig. 25 of the modified device for feeding the strip aligning means.

Fig. 27 is a section on line 27—27 in Fig. 26.

Fig. 28 is an enlarged section on line 28—28 in Fig. 26 and

Fig. 29 is a perspective section of the strip aligning means and the modified means for feeding same.

The main frame 1 of the machine may be of any desired construction, being shown provided with a main drive shaft 2 which may be operated by a motor 3 or in any desired way. The strip of steel A to be sharpened may be supplied on a reel 4 journaled at 5 on frame 1 in a known way. The strip A is shown provided with spaced apertures a adapted to receive individual and separate supporting and aligning means B, such as steel balls. The strip travels through a guideway 6, shown located between spaced portions of longitudinal bars 7 which may be secured together by screws 8, (Figs. 20—23), which bars may be supported on frame 1 by means of standards 9, (Fig. 2). The guideway 6 fits the sides of the

strip A sufficiently snug to permit the strip to slide and to resist lateral thrusts of the sharpening wheels or disks to be described. Between the bars 7, and in communication with the guideway 6, is a longitudinal channel 10, shown formed along the inner surfaces of the bars 7. The dimensions of the channel 10 are such as to support the strip aligning members or balls B and prevent them from having vertical and lateral movement 10 while traveling through the channel. The balls act as aligning means for strip B by entering the apertures *a* therein and thereby resist vertical or edgewise movements of the strip during its travel along the guideway.

15 The balls or aligning means or members are fed to the guideway 6, and from the guideway to be returned thereto, for supporting the strip, as follows: Communicating with the charging end of the guideway 6 is a raceway or tube 11 for 20 the balls, which rises therefrom a suitable distance and descends to a ball-receiving location, as illustrated in Fig. 3, whereby the balls may roll by gravity or be forced toward the channel 10, from the upper part of the raceway. The balls accumulate (as hereinafter described) at the lower portion 25 of the raceway, and are raised therefrom, successively, by means of one or more rockable pawls 12 which are pivotally carried by a rotative member 13, (Figs. 9, 10 and 12). A block or 30 fitting 14 at the lower end of the raceway has a channel 15 communicating therewith and a vertical slot 16 in one side, (Fig. 11), which receives the reduced end 12a of a pawl, whereby the latter may engage and raise the balls, successively, into 35 the raceway. Spaced pawls are shown pivoted at 17 on member 13 and are normally spring-pressed against stops 18, on said member, by springs 19 connected to said pawls and to said member, (Fig. 10), the ends 12a of the pawls normally 40 extending beyond the periphery of the member. At an appropriate position is a stop 20 to be engaged by the inclined edge portion 12b of the pawl to tilt the latter rearwardly to release it from a ball, during rise of the pawl, (Fig. 10), 45 and as the pawl passes from said stop the pawl will move back against top 18 for engagement with another ball, and so on successively as member 13 rotates. A stop dog 21 is normally spring-pressed into the path of balls rising into the 50 raceway 11, the dog being shown pivoted at 22 and pressed by spring 23 into channel 15. The inner under surface of dog 21 is shown inclined at 21a, (Fig. 12). With the dog in the position shown in Fig. 12, the balls or members B in race- 55 way 11 will be sustained, and when a pawl 12 engages a ball and lifts it the ball will ride against the surface 12a and move the dog outwardly to permit the ball to pass, whereupon the dog will snap back under the raised balls, and so on successively for each ball. In order to permit the 60 pawls to operate against the balls in the raceway without injury I provide frictional means for rotating member 13, as follows: A shaft 24 is journaled in housing 24a and retained by col- 65 lar 24b, said housing being secured to the main frame 1, (Fig. 3), and member 13 is secured to said shaft, as by screw 25, a pulley 26 being shown rotatively carried by said shaft, (Fig. 9). A friction clutch device connects shaft 24 with pulley 70 26, including a member 27 secured on shaft 24 and carrying a spring-pressed pin 28 engaging a disk 29 that is spring pressed against a friction disk 30 that bears against pulley 26. If the pressure of a pawl 12 against the line of balls in the 75 raceway is too great (since the balls are main-

tained under some pressure against the strip A at the delivery end of the raceway), the pawl will be retarded and the friction driving devices will slip to retard the pawl until the pressure is properly relieved, whereupon the pawl and member 5 13 may rotate as required.

At the delivery end of the raceway 11 the end-most ball or member B bears against the unperforated portion of the traveling strip A, in the line of the apertures *a*, and as the apertures successively pass the row or line of balls the end-most ball will enter an aperture, and so on successively, to be propelled by and with the strip along the guideway 10, the balls advancing by gravity and pressure to enter the apertures *a*, 15 (Fig. 15).

The strip A may be propelled by any desired means. I have shown pressure rolls 31 and 32 bearing against opposite faces of strip A, and suitably journaled on the main frame, (Figs. 2 20 and 18). A worm wheel 33 on the shaft of roll 32 in mesh with a worm 34 operated by a belt 35 on pulleys 36 and 37, driven by shaft 2, causes the rolls 31 and 32 to feed strip A at the proper speed, in the direction of the arrows in Figs. 2 25 and 17. The balls B will roll and/or be forced into the apertures *a* of the strip A successively as the strip passes the raceway 11, and as the balls roll along the channel 10 the strip will be supported and vertical movement thereof resisted 30 to permit sharpening its edge or edges as the strip travels.

To resiliently adapt the balls or members B to the channel 10 I provide a spring-pressed member or dog 38 adjacent to the meeting ends 35 of channel 10 and raceway 11, located in a recess 39 in a bar 7 and pivotally supported at 40, (Figs. 15 and 16). A spring 41 normally presses the member or dog 38 toward the balls to assist them in proper location within the apertures *a* 40 of strip A.

At the delivery end of channel 10 is a return guide or race 42 for the balls, which communicates at the upper end with said channel and at the lower end with the vertical channel 15, said 45 guide or race inclining downwardly to deliver the balls by gravity to channel 15, (Figs. 2 and 10). At the delivery end of channel 10, opposite the guide or race 42, is a stop or block 43, shown 50 having a curved inner surface 43a, (Figs. 18 and 19), to cause the balls, successively, to be pushed out of the apertures *a* of strip A, to travel through the guide or race 42, after the edge portion or portions of the strip have been treated or sharpened. Thus, as the strip propels the balls with it 55 along channel 10 and the balls successively engage the stop 43 they will be deflected from the strip, which may pass on.

Any suitable means may be provided for treating or sharpening the edge or edge portions of 60 the strip. I have illustrated a pair of adjacent grinding disks 44 and 45, journaled in uprights 46 and 47 on frame 1, to grind facets on opposite sides of the upper edge of strip A, (Figs. 1 and 20). Pulleys on the shafts of the disks receive 65 belts 48 from pulleys 49 on shaft 2 for driving the disks in the appropriate directions. Other similar disks 50 and 51 may operate along the lower edge portions of the strip A for grinding facets therealong. The disks 50 and 51 may be rotated 70 in the appropriate directions by means of belts 52 on pulleys on the shafts of said disks and on pulleys 53 on shaft 2. I have also shown honing or stropping disks 54 and 55 (Figs. 1, 5 and 22), of the grooved or interlocked variety, above the 75

strip A for finishing the ground upper edges of the strip, said disks being driven by belts 56 on pulleys 57 on shaft 2. Corresponding disks at 58 and 59 (Figs. 1 and 23) may operate on the

5 lower ground edge portions of the strip A for honing or stropping the latter, said disks being driven by belts 60 on pulleys 61 on shaft 2.

The finished strip may be received on a take-up reel 62 journaled on frame 1, or the strip may 10 be cut off into suitable lengths for razor blades, or for other desired purposes. The reel 62 may be rotated by slip cord or belt 63 from a pulley 64a on the shaft of roll 32 and a pulley connected with said reel, (Figs. 1 and 2). Belt 63 15 is caused to slip on pulley 64 as the diameter of the wound strip increases.

In the modified means for feeding the aligning members shown in Figs. 25 to 29 inclusive, I provide housings 64 and 65 suitably secured to the 20 main frame 1. Spaced shafts 66 and 67 are journaled in housing 64. Gears 68 and 69 are secured to shafts 66 and 67 and in mesh with each other to enable both shafts to rotate in unison. Pulley 70 is secured to shaft 67 and is driven by belt 71 25 from pulley 72, which pulley is secured to main shaft 2 (Figs. 25, 26 and 27). Spaced shafts 73 and 74 are mounted in housing 65 and secured in said housing by screws 75 and 76. Pulleys 77 and 78 are rotatively mounted on shafts 75 30 and 76 and retained by collars 79. Similar pulleys 80 and 81 are secured to shafts 66 and 67 by screws 82 and 83. Belts 84 and 85 are stretched over pulleys 77 and 78 on housing 65 and pulleys 80 and 81 on housing 66, so that when pulley 35 70 is revolved, belts 84 and 85 will be driven in the direction indicated by the arrows (Figs. 25 and 28). The lower walls of raceway or tube 11 are cut away at 86, allowing tube to fit between spaced feeding belts 84 and 85 and connects with return channel 15 so that aligning 40 balls or members from race 42 can enter between and contact with feeding belts 84 and 85 to be frictionally propelled into raceway 11 and toward the perforated strip A as indicated in Figs. 45 28 and 29.

When the balls or members B have filled the space in the raceway 11 between the feeding belts 84 and 85 and the perforated strip A, the belts continuing to travel, will rub against the surfaces 50 of the balls, thereby frictionally exerting an upward force to the balls so that when an aperture of the perforated strip A presents itself at the delivery end of raceway 11, the endmost ball will be forced into the aperture and so on successively into the other apertures.

In accordance with my invention I am enabled to accurately guide a traveling steel strip to align it in a vertical direction, to resist vertical thrusts of tools thereon, such as grinding, honing or 55 stropping disks or wheels, and to release the strip from the aligning means in a simple and effective way by the utilization of the individual and separate balls or members B which enter and depart from the apertures in the strip before and after the operation thereon of the disks or tools, the balls engaging the upper and lower walls of apertures a, while at the same time the guiding bars 7 guide the strip as it travels to resist lateral thrusts or pressure of the disks or tools. The 60 bars 7 are provided with longitudinally extending grooves 7a which receive the sharpened edge portions of the strip, and since the balls or members B in the channel 10 keep the strip from vertical movements, the edges of the strip are held in 65 proper relation to the grinding, honing or strop-

ping wheeels and the sharpened edges of the strip are kept out of contact with parts of the machine.

In the operation of the machine described herein as illustrative of a preferred embodiment of the invention, the metal strip A, to be operated upon, may be supplied on a reel 4 journaled at 5. The strip A is provided with spaced apertures or cutaway portions a, which may be of any desired contour, and passes through a guideway 6 formed in the longitudinal bars 7, shown more particularly in Fig. 6, and is received at the opposite end of the machine on a take-up reel 62 journaled on the frame of the machine. If desired, the strip may be cut into suitable lengths 10 for razor blades or the like as it leaves the machine. In passing along the guideway 6 through the machine, the upper edge of the strip may be ground and sharpened by disks 44 and 45 (Figs. 1, 2, 4 and 20) and the lower edge may be ground 15 and sharpened by similar disks 50 and 51 (Figs. 1, 2 and 21). Thereafter, the sharpened upper edge of the strip may be stropped or honed by the disks 54 and 55 (Figs. 1, 2, 5 and 22) and the lower edge may be stropped or honed by the 20 disks 58 and 59 (Figs. 1, 2, and 23). The several honing and sharpening disks may be suitably driven by pulleys and operatively connected to the main drive shaft 2 (Fig. 2) extending longitudinally of the machine.

The strip, during its passage through the machine, is held with its edges out of contact with the bottom and top of the guideway 6 by means of members, such as the balls B passing along the guideway 10, provided therefor. The balls 30 B fit into suitable apertures in the strip to guide it and to hold it accurately in position during its movement through the machine and during the several operations performed thereon. Preferably, the balls B are fed to the channel 10 in 35 the guideway 6 and to the apertures in the strip by an inclined chute 11 leading to the channel 10, as shown more particularly in Figs. 1, 13, 14, 15 and 16. As each aperture in the strip is presented, a ball enters and is carried along the 40 channel 10 until it reaches the end thereof, where the curved member 43 ejects the balls from the apertures into the downwardly extending chute 45 42, as shown more particularly in Figs. 1, 17, 18, and 19. The balls roll by gravity along the chute 50 43 until they reach the front end of the machine, as shown in Fig. 2. The vertical portion of the tube 11 has a slot therein and the pawls 12 move upwardly along the slot to raise the balls past the stop dog 21 into the delivery end of the chute 55 11, where they again enter the channel and the apertures in the strip A. Another form of device, comprising a pair of belts 84 and 85, is shown in Figs. 25 to 28, for raising the balls into the delivery end of the chute 11.

As various changes may be made in the form, construction and arrangement of parts without departing from the spirit and scope of the invention and without sacrificing its advantages, it is to be understood that all matter herein is to 65 be interpreted as illustrative and not in a limiting sense.

Having now described my invention what I claim is:

1. Aligning means for a metal strip to be sharpened including guiding means for the strip aligning members for said metal strip, means to guide said aligning members, means to propel the strip, a raceway communicating with the guide for the members adapted to receive said aligning mem- 75

bers, a movable pawl to advance the members in the raceway, means to operate the pawl, and a dog to resist backward movement of the members along the raceway.

5. Aligning means as in claim 1 in which the dog is provided with means to be engaged by the pawl for moving the dog out of the path of the aligning members.

3. Aligning means as in claim 1 provided with 10 means to move the pawl to release the dog to permit the latter to oppose the members in the raceway.

4. Aligning means for a traveling apertured metal strip to be sharpened including guiding means for the strip and a channel for strip aligning members, a raceway communicating with the channel, means to advance aligning members through the raceway to apertures in the strip for travel through the channel, discharge means in 15 the channel to engage members in the apertures of the strip to discharge said members from the strip into the return guide and a return guide for the members in communication with the channel, said guide being in communication with the raceway to return discharged members to said advancing means.

5. Aligning means as in claim 4 in which the advancing means are below the channel and the return guide extends in a downward direction 30 from the channel to the advancing means to direct the discharged members thereto by gravity.

6. Aligning means for an apertured metal strip to be sharpened including guiding means for the strip and a channel for strip aligning members, a raceway for the aligning members communicating with the channel, a yieldable member to engage the aligning members in the channel adjacent to the delivery end of the raceway to assist in locating the members in the apertures of the strip, means to advance the members through the raceway to the channel, and means to propel the strip through the guiding means.

7. Aligning means for a continuous apertured metal strip to be sharpened, including guiding means for the strip, said means having a channel, means to propel the strip along the guiding means and the channel, guiding means communicating with the channel to successively direct individual disconnected aligning members 45 for insertion into the apertures of the strip within the channel, means separate from the strip to engage and discharge the members successively from said apertures of the strip and from said channel, and a raceway for receiving the discharged members and for returning them successively into the apertures of the strip.

8. Aligning means for an apertured metal strip to be sharpened, including guiding means for the strip, said means having a channel, means to propel the strip along the guiding means and the channel, guiding means communicating with the channel to separately and successively advance disconnected aligning members into the channel and into the apertures of the strip during the travel of the latter, means separate from the strip to engage and discharge said members successively from the travelling strip, and raceway for returning the discharged members in a closed path successively into the apertures of the strip.

70 9. Aligning means for a recessed metal strip to be sharpened, including guiding means for the strip, said means having a channel, means to propel the strip along the guiding means and the channel, a raceway communicating with the channel, and means to successively advance in-

dividual disconnected aligning members through the raceway into the recesses in the strip within the channel, means to cause said members to be discharged from the strip and the channel, and a return guide to receive and return discharged members successively to the advancing means, whereby said aligning members move in a closed path.

10. Aligning means for a recessed metal strip to be sharpened, including guiding means for the strip, said means having a channel, means to propel the strip along the guiding means and the channel, a raceway communicating with the channel, and means to advance individual disconnected aligning members through the raceway into the recesses in the strip within the channel, said advancing means including a movable pawl to engage the members to advance them to the raceway and also including means to operate said pawl to successively advance the members, means to cause said members to be discharged from the strip and the channel, and means for returning the discharged members to said raceway.

11. Aligning means for a recessed metal strip to be sharpened, including guiding means for the strip, said means having a channel, means to propel the strip along the guiding means and the channel, a raceway communicating with the channel, means to advance individual disconnected aligning members through the raceway into the recesses in the strip within the channel, means to cause said members to be discharged from the strip and from the channel and means for returning the discharged members to said raceway, said advancing means including a rotative member, means to operate the rotative member, a pawl pivotally carried by the member and having a portion to engage and advance aligning members into the raceway, and means to resist the return of the advanced members.

40 12. Aligning means for a slotted metal strip to be sharpened, including guiding means for the strip, said means having a channel, means to propel the strip along the guiding means and the channel, a raceway communicating with the channel, and means to forcibly advance individual aligning members through the raceway into the slots of the strip within the channel, means to discharge the members from the slots and from the channels, and means for returning the discharged members to said raceway, said forcing means for the aligning members including feeding means to engage the walls of the members to advance them through the raceway.

45 13. Aligning means for a metal strip to be sharpened, having cutaway portions therein, including guiding means for the strip, said means having a channel, means to propel the strip along the guiding means and the channel, a raceway communicating with the channel, and means to forcibly advance individual aligning members through the raceway into the cutaway portions of the strip within the channel, and means to discharge the members from the cutaway portions and from the channel into said raceway, 50 said forcing means including belts to engage the walls of the members to advance them through the raceway.

70 14. Aligning means for a metal strip to be sharpened, having cutaway portions therein, including guiding means for the strip, said means having a channel, means to propel the strip along the guiding means and the channel, a raceway communicating with the channel, and means to forcibly advance individual aligning members 75

- through the raceway into the cutaway portions of the strip within the channel, and means to discharge the members from the cutaway portions and from the channel into said raceway, 5 said forcing means including spaced frictional feeding belts to engage opposite walls of the aligning members to feed said members through the raceway and into the cutaway portions of the strip, and means to operate said belts.
10. 15. In a device of the class described, the combination of a guideway for a strip of material to be sharpened, said guideway being adapted to receive individual disconnected aligning members for aligning said strip, means for feeding said aligning members to said guideway, means for removing said members from the guideway, and a raceway for returning said discharged members to the feeding means, said feeding means being effective upon the members in said race- 15 way.
16. In a device of the class described, the combination of a guideway for a strip of material to be sharpened, said guideway having a channel associated therewith adapted to receive individual disconnected aligning members for aligning said strip, means for sharpening an edge of the strip, means for feeding said aligning members one at a time to said channel to guide the strip past the sharpening means, means for removing 20 said members from the channel after they have passed the sharpening means, and a raceway for returning said discharged members to the feeding means whereby said members move in a closed path and in a single row.
25. 17. In an aligning means of the class described, the combination of a guideway for a strip of material to be sharpened, said strip having recesses therein, said guideway being adapted to receive individual disconnected aligning members for aligning said strip, and friction driven means for feeding said aligning members to said guideway and for forcing said members into said recesses.
30. 18. In an aligning means of the class described, the combination of a guideway for a strip of material to be sharpened, said strip of material having recesses therein, said guideway being adapted to receive individual disconnected aligning members for aligning said strip, friction driven means for feeding said aligning members to said guideway and for forcing said members into said recesses, means for removing said members from the guideway, and means for returning said discharged members to the feeding means.
35. 19. In an aligning means of the class described, the combination of a guideway for a strip of material, said guideway being adapted to receive individual disconnected aligning members for said strip to guide the strip along said guideway and prevent damaging of the edge thereof, a raceway adapted to receive said individual disconnected members from one portion of the guideway and to deliver them to another portion thereof, a portion of said raceway being inclined upwardly, and means for forcing said members along said upwardly inclined raceway into said guideway.
40. 20. In an aligning means of the class described, the combination of a guideway for a strip of material, said guideway being adapted to receive aligning members for holding said strip in proper position therein, a raceway for said aligning members from one portion of said guideway to another portion thereof, and a belt for engaging 45 said members in said raceway for forcing said members along the raceway into said guideway.
45. 21. Aligning means for a continuous apertured metal strip to be sharpened, including guiding means for the strip, said means having a channel, means to propel the strip along the guiding means and the channel, an inclined guideway adapted to receive a series of aligned disconnected aligning members and communicating with the channel to successively direct said members for insertion into the apertures of the strip within the channel, said aligning members being adapted to move with the strip past the sharpening means, means for delivering aligning members to said inclined guideway, a raceway for conveying the aligning members to said delivering means, and means separate from the strip to engage and positively eject the members successively from said apertures of the strip and from said channel into said raceway.
50. 22. Aligning means for an apertured metal strip to be sharpened, including guiding means for the strip, said means having a channel, means to propel the strip along the guiding means and the channel, disconnected spherical aligning members for aligning the strip in said guiding means, a raceway having an inclined portion communicating with the channel to separately and successively advance the spherical aligning members into the channel and into the apertures of the strip during travel of the latter, and means 55 separate from the strip and projecting into the channel on one side of the strip to engage and expel said spherical members successively from the apertures of the travelling strip into said raceway.
55. 23. Aligning means for a continuous metal strip having recesses therein, including guiding means for holding the strip in a substantially vertical plane, said means having a channel, means to propel the strip in vertical position along the guiding means and the channel, disconnected spherical aligning members adapted to fit into said recesses and into said channel to align the strip, a raceway communicating with the channel and extending laterally therefrom, and means to successively advance individual spherical members 60 through the raceway into the recesses in the strip within the channel and means in the channel to positively eject said spherical members from the strip and the channel, and means for receiving the ejected members and delivering them to said advancing means.
60. 24. Aligning means for an apertured metal strip to be sharpened, including guiding means for the strip, a channel associated with said guiding means, strip aligning members adapted to fit in said apertures and to pass along said channel, a raceway communicating with the channel to guide said members thereto, a pawl to advance the members into the raceway, a rotative member 65 pivotally carrying the pawl, and means to rotate said member including friction means to permit the rotation of the member to be retarded.
65. 25. Aligning means as in claim 24 provided with a stop to engage the pawl to release it from the aligning members.
70. 26. Aligning means as in claim 24 provided with a stop to engage the pawl to release it from the aligning members, and a dog to resist return of the members advanced by the pawl.
75. 27. Aligning means for a continuous apertured metal strip to be sharpened, including guiding means for the strip, said means having a channel, means to propel the strip along the guiding means

and the channel, guiding means communicating with channel, means to propel individual disconnected aligning members along said guiding means and to force them into the apertures of the strip within the channel, means separate from the strip to engage and discharge the members successively from the apertures of the strip and from the channel, and a raceway for receiving said discharged members and delivering them to said propelling means.

28. Aligning means for an apertured metal strip to be sharpened, including guiding means for the strip, said means having a channel, means to propel the strip along the guiding means and the channel, a raceway adapted to receive individual aligning members from the channel and return them to the channel, and positive operating means to engage and advance the individual aligning members through the raceway into the apertures of the strip within the channel and means to dis-

charge the members from the apertures and from the channel into the raceway.

29. Aligning means for a continuous apertured metal strip to be sharpened, including guiding means for the strip, means to propel the strip along the guiding means, means to successively insert individual disconnected spherical aligning members into the apertures of the strip in combination with sharpening means for the strip, means to cause the strip to carry the aligning members within the apertures of the strip past said sharpening means, means to engage and discharge the spherical aligning members from the apertures of the strip, and means including a raceway adapted to receive the spherical members discharged from the apertures of the strip on one side of the sharpening means and to return the spherical members to the apertures in the strip ahead of the sharpening means.
